COOLING ARRANGEMENT FOR GAS TURBINES

Samuel R. Puffer, Lynnfield Center, Mass., assignor to General Electric Company, a corporation of New York

Application June 28, 1939, Serial No. 281,576

2 Claims. (Cl. 60—41)

The present invention relates to cooling arrangements for gas turbines, particularly of the type of turbines which include a bucket wheel supported on an overhung shaft and having a row of buckets arranged to discharge gases directly into the atmosphere. Such turbines are often used on aircraft for driving superchargers or generators. During operation the bucket wheel may be subject to excessive heat by the gases discharged therefrom. This is particularly the case where the bucket wheel is mounted so that some of the gases discharged from it are forced towards a central portion thereof by the action of the slip stream.

The object of my invention is to provide an improved construction and arrangement of gas turbines whereby such turbines may be operated safely with gases at high temperatures of the order of 750° C. and above.

For a consideration of what I believe to be novel and my invention, attention is directed to the following description and the claims appended thereto in connection with the accompanying drawing.

In the drawing Fig. 1 illustrates a sectional view of a gas turbine arrangement for aircraft embodying my invention, and Fig. 2 is a perspective view of a part of Fig. 1.

The arrangement comprises an axial flow gas turbine with a solid bucket wheel 10 mounted on an overhung shaft 11 adjacent a bearing 12 of a supercharger 13. The bucket wheel 10 has a disk with a rim 14 on which an annular row of buckets 15 is mounted. The outer ends of the buckets are connected by a band 16. An annular nozzle box 17 is mounted on one side of the bucket wheel and has an inlet portion 18 for receiving gases from a suitable source, such as the exhaust manifold of a combustion engine, not shown. The nozzle box includes a row of nozzles 19 adjacent the buckets 15 for properly directing operating gas to the bucket wheel. The nozzle box in the present instance is mounted on studs 20 formed on the casing of the supercharger 13 by means including a wall 21 which also serves to protect the bearing 12 from heat radiated from the nozzle box 17. During operation high temperature gases are conducted from the nozzle box to one side of the bucket wheel passing through the passages formed between adjacent buckets and issuing from the other side of the bucket wheel directly into the atmosphere.

The bucket wheel is subject to the heat of the gases, as pointed out above, especially when the direction of discharge into the atmosphere is sub-

stantially perpendicular to the direction of the slip stream. The direction of discharge has been indicated in the drawing by an arrow 22 and the direction of the slip stream has been indicated by an arrow 23. The latter in the present instance is parallel to a diameter of the bucket wheel and perpendicular to the direction of discharge of gases, as well as to the axis of rotation of the wheel. With reference to the direction of the slip stream, the upper portion of the bucket wheel 10 in the drawing is leading and the lower portion of the bucket wheel is trailing. In such arrangement the slip stream forces gases issuing from the leading portion of the bucket wheel towards a central portion thereof and causes excessive heating.

This difficulty is overcome in accordance with my invention by the provision of a device protecting and effectively cooling the bucket wheel disk. The device comprises a cap 24 adjacent the outer face of the bucket wheel disk, and concave-shaped towards the latter. The cap is slightly smaller in diameter than the maximum diameter of the rim. Similar caps are disclosed in the application of Chester W. Smith, Serial No. 281,562, filed on the same date and assigned to the same assignee as the present application, and since issued as Patent No. 2,364,037. A portion of the cap is cut out to form an opening 25 and a box-shaped structure 26 is secured to the cap, preferably by fused metal, to circulate cooling air through the space 27 formed between the cap and the bucket wheel. This box-shaped structure 26 forms an inlet 28 for receiving cooling air. In the present instance the inlet 28 opens in the direction of the slip stream whereby the slip stream forces air into the space. The lower portion of the structure 26 forms an outlet 29 for discharging cooling air from the space 27. The box-shaped structure has an outer plane wall 30. In order to force the cooling air towards the central portion of the bucket wheel and properly to guide the air thereafter through the outlet 29 a deflecting and guiding plate 31 is disposed inside the box-shaped structure 26 and secured to the walls thereof by means including flaps 32. During operation a continuous flow of cooling air through the structure 26 towards the bucket wheel takes place. This air is forced into the inlet 28 by the relative motion of the air in the slip stream, and exhausted through the outlet 29 by the downstream effect of the same slip stream. The outer rim of the cap 24 forms a relatively close clearance with the rim 14 of the bucket wheel so that little cooling air is discharged

through the clearance. This cooling air prevents entry of hot gases discharged from the bucket wheel, particularly near the leading portion thereof. As the discharge of cooling air through said clearance is small it does not appreciably interfere with the free discharge of gases from the bucket wheel. The cooling device is mounted on the nozzle box 17 by means of brackets 33 and 34 fastened to studs 35 and 36 respectively on the nozzle box 11.

What I claim as new and desire to secure by Letters Patent of the United States is:

1. Gas turbine arrangement for aircraft comprising a bucket wheel for directly discharging into the atmosphere and a device located on the discharge side of the wheel for cooling the central portion of the wheel, said device comprising a cap adjacent the wheel and having a rim forming a close clearance with the wheel, said cap having an opening, a box-shaped structure fastened to the cap around said opening and forming an inlet conduit for receiving cooling air to

be conducted to the space formed between the wheel and the cap and a discharge conduit for discharging cooling air from said space directly into the atmosphere with the discharge located substantially diametrically opposite the inlet.

2. Gas turbine arrangement for aircraft comprising a bucket wheel, an annular nozzle box located on one side of the bucket wheel to conduct operating gas thereto, and a cooling device located on the other side of the bucket wheel and supported on the nozzle box, said device comprising a cap concave-shaped towards the wheel and forming a space therewith, a structure secured to the cap and forming inlet and outlet conduits for cooling air communicating with diametrically opposite portions of the space between the cap and the wheel and a deflector and guiding wall within the structure and secured to the walls thereof for forcing cooling air entering the inlet conduit towards the wheel and guiding the air from said space towards the outlet conduit.

SAMUEL R. PUFFER.
